UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

CHAIN-STITCH SEWING-MACHINE.

1,127,067.

Specification of Letters Patent.

Patented Feb. 2, 1915.

Application filed January 2, 1911. Serial No. 601,655.

To all whom it may concern:

Be it known that I, JAMES R. MOFFATT, a citizen of the United States, residing at Chicago, in the county of Cook, State of Illinois, have invented certain new and useful Improvements in Chain-Stitch Sewing-Machines, of which the following is a description, reference being had to the accompanying drawing and to the letters and figures of reference marked thereon.

The invention relates to new and useful improvements in chain stitch machines, and more especially to machines of this character in which a threaded needle co-operates with a non-thread-carrying looper to form a series of single chain stitches.

An object of the invention is to provide means for properly supporting the needle loop so as to present the same for the entrance of the needle, whereby the loops of thread may be properly interlocked, and all liability of the skipping of stitches avoided.

In the drawings which show by way of illustration one embodiment of the invention:—Figure 1 is a view partly in section and with parts broken away, of the forward end of a sewing machine embodying my improvements. Fig. 2 is a sectional view through the throat plate, also showing the presser foot, the needle and the looper, and the feed at the time when the looper is entering the needle loop. Fig. 3 is a similar view showing the position of the parts when the needle is about to enter the needle loop, held by the looper. Fig. 4 is a top plan view of the throat plate showing in dotted lines the looper and needle loop spreader. Fig. 5 is a bottom plan view of the throat plate.

The sewing machine as herein shown, consists of a bed plate 1, on which is mounted the usual work support 2. A needle bar 3 is reciprocated in the overhanging arm 4, by a needle lever 5 which is connected to the needle bar through the link 6. Said needle bar carries a needle 7 at the lower end thereof. The presser bar 8 is also mounted in the overhanging arm 4, and carries a presser foot 9 which may be of the ordinary construction and which co-operates with a feed dog 10 mounted beneath the work support to reciprocate in the usual manner in this type of machine.

Co-operating with the needle 7 is a non-thread-carrying looper 11 which is mounted

on a looper carrier 12 pivoted to a looper support 13. The looper carrier 12 is vibrated on its pivotal support by the usual link 14. The looper support 13 is also vibrated on its bearing by a link connection 15 with the end of the main shaft.

The above parts are of the usual construction, and will not need further description in order that the present invention may be understood.

The needle penetrates the material and as it is retracted, throws out the usual needle loop which is entered by the looper 11. The looper moves forward to the end of its stroke, and then laterally so as to position the needle loop held by the looper for the entrance of the needle on the next descent thereof. The looper is not only moved laterally but is slightly retracted before the point of the needle reaches the needle loop. As the looper is retracted, one limb of the needle loop which is moving with the looper will be brought into contact with a spreading finger 16, which is secured to the under side of the throat plate 17 by a screw 18. This spreader will retain temporarily the strand of the needle loop which is engaged thereby, and the further retracting movement of the looper causes the needle loop to be spread or positioned in a plane approaching a horizontal plane so as to open widely the needle loop for the entrance of the needle.

I have found in practice that where the needle loop which extends from the looper to the previous needle puncture in the fabric is slightly loosened by the retracting movement of the looper that said needle loop is liable to twist and become positioned so that the needle would pass outside of the needle loop and thus cause the machine to skip stitches.

To aid in supporting the needle loop so that the same cannot twist or be improperly positioned, I have provided a bar 19 which is located directly underneath the needle slot 20 in the throat plate, and extends across the needle slot intermediate the ends thereof. Said bar as herein shown, is attached to the throat plate, although it is obvious that any suitable means may be provided for supporting the bar substantially in the position stated.

When the feed of the fabric occurs, the needle loop extending from the previous

needle puncture around the looper will be brought in contact with said bar, and will thereby be supported at a point between the looper and the previous needle puncture, 5 where the needle thread is interlocked with the previous needle loop in the chain of stitches. This supporting of the needle loop as above noted, will hold the needle loop with both strands thereof in a plane ap- 10 proaching a horizontal plane, and will also tend to separate the two strands so that the needle will with certainty, enter into said needle loop. This bar which tends to place the loop in a horizontal plane at the base 15 thereof, coöperates with the loop-spreading finger 16 in properly positioning the needle loop for the entrance of the needle. In order that the needle may enter the needle loop, said loop must not only be spread, but 20 must lie as near horizontally as possible, in order that the needle may enter between the strands of the loop. The spreading finger opens up the loop and the bar coöperating therewith tends to position the loop hori- 25 zontally.

It is obvious that minor changes in the details of construction may be made without departing from the spirit of my invention.

Having thus particularly described my in- 30 vention, what I claim as new and desire to secure by Letters Patent, is:—

1. In a sewing machine, the combination of feeding mechanism, a needle, a non-thread-carrying looper, means for supporting said looper whereby the same may be moved in a direction substantially at right angles to the line of feed, means for oscillat- 35

ing said looper into and out of the needle loop, means for moving said looper laterally to position the needle loop for the entrance 40 of the needle, a bar and means for supporting said bar in a position substantially at right angles to the line of feed and adjacent the path of the needle in rear thereof, whereby the needle loop on the looper is sup- 45 ported by said bar.

2. A throat plate having a needle slot formed therein, a loop retainer secured to said throat plate in advance of the needle slot and having a projecting finger for en- 50 gaging one strand of the needle loop, and a bar secured to said throat plate and extending across said needle slot in rear of the portion of said slot entered by said needle.

3. In a sewing machine, the combination 55 of a needle, a looper, a throat plate having a needle slot formed therein, a loop retainer secured to said throat plate in advance of the needle slot and having a projecting finger for engaging one strand of the needle 60 loop, whereby the same is spread for the entrance of the needle, a bar secured to said throat plate and extending across the needle slot in rear of the portion thereof entered by the needle, whereby the needle loop ex- 65 tending around the looper and engaged by said loop retainer, is supported by said bar.

In testimony whereof I affix my signature, in presence of two witnesses.

JAMES R. MOFFATT.
